BRAKE BEAM

Carl R. Moline, Homewood, Ill., assignor to
 American Steel Foundries, Chicago, Ill., a corporation of New Jersey

Application April 7, 1945, Serial No. 587,098

5 Claims. (Cl. 188—228)

1

A brake beam is the immediate supporting structure for the two brake heads and two brake shoes acting upon a given pair of wheels of a railway car truck. In freight service, the practically universal type is of truss construction consisting primarily of tension and compression members fastened at the ends and separated at the middle by a strut or fulcrum to which the truck brake lever is attached. As a matter of practical construction, it is now conventional to make each brake head include a sleeve portion which telescopes over the corresponding end of the compression member and also the tension member, and thereby forms the immediate fastening between the adjacent ends of the compression and tension members.

The A. A. R. Standard No. 15 Brake Beam (Car Builders' Cyclopedic, 1943, page 1000, Manual, pages E-84-87) includes a compression member formed of a 3" x 1 $\frac{1}{8}$ " channel,

5'0" $\frac{1}{2}$ " $\pm\frac{1}{4}$ "

on the brake beam center, and the tension member is 1 $\frac{1}{4}$ "-diameter rod equipped at each end with 1 $\frac{1}{4}$ " standard hexagonal nuts, 7 threads per inch. As a preliminary to the assembly, the compression member has its ends bent toward the tension member to give it a camber of $\frac{1}{8}$ " $\pm\frac{1}{8}$ " $\pm\frac{1}{8}$ "; and, while thus held, the 1 $\frac{1}{4}$ " standard hexagonal nuts are applied and set up, and thus the resiliency of the compression member puts the entire truss structure of the beam under appropriate "tension" to secure rigidity and prevent rattling. After the assembly is made, the ends of the tension member are riveted over.

Variations in the structural members, their size, etc., are shown in the Car Builders' Cyclopedic, 1943, page 995, and in the Manual, page E-82.

This construction of brake beam, in all the allowable variations exercised by a variety of producers, has two outstanding faults, both of which result in very serious damage: First, the tension members break at the thread close to the nut at one end or the other. Such a break immediately releases the fastening for that end of the beam structure, permits the compression member to recover partially or wholly from the bending above described, and frees the brake head with the attached brake shoe from any fastening. Such a break makes it possible for the "brake beam acceleration" to throw the brake head laterally with such violence as to do serious damage to a train on an adjacent track. It also permits

2

the parts of the brake beam to strike the track at the rail, at the crossing, or at the switches, doing serious damage, and by some sort of maneuver difficult to explain parts of the brake beam are sometimes found wrapped around the axle.

Second, it not infrequently happens that a brake shoe is lost off the brake head. At the next brake application, the brake head is brought against the wheel. This need only be repeated a few times in order to ruin the brake head, which must be then replaced before the brake beam can be put back into service. With the construction conforming to A. A. R. Standard No. 15, above referred to, this means that the tension member must be cut away in order to get off the injured brake head, and a new tension member must be supplied with a new brake head. This makes the repair very costly.

20 The principal object of this invention is to overcome these and many other faults in the present-day conventional freight car brake beam, and, generally speaking, this is accomplished by eliminating entirely the threaded ends of the tension member and the use of cooperating nuts held in place by riveting over the ends of the tension member.

The preferred way of accomplishing this is to make the tension member in two parts, each part having an integral upset head which is engaged with one of the brake heads and the brake beam strut, while the compression member is held in a fixture that bends it to the extent of the required camber, or a little bit more; and, upon release, the rebound or spring-back of the compression member serves to fasten the parts together and hold them under the desired tension.

In the accompanying drawing showing the preferred embodiment—

40 Fig. 1 is a plan view of the finished brake beam;
 Fig. 2 is an elevation of the brake beam strut, the compression member being shown in section;
 Fig. 3 is a perspective view of one of the tension members;
 45 Fig. 4 is a section on the line 4—4 of Fig. 1;
 Fig. 5 is an enlarged plan view of little more than one-half of the brake beam structure in the position the parts may assume just prior to putting the compression member in the jig to give it camber;
 50 Fig. 6 is a similar view showing a little more than one-half of the brake beam just after the parts have been put in the position of final assembly; and
 55 Fig. 7 is an enlarged detail of the socket at the

end of the brake beam strut where the inner ends of the tension members are made fast.

But these drawings and the corresponding, specific description are used for the purpose of disclosure only and are not intended to impose unnecessary limitations on the claims, for it is realized that the fundamentals of this invention may be embodied in a great variety of forms without departing from its spirit.

The compression member is shown at 10, the tension members at 11, the strut at 12, and the brake heads at 13.

The compression member 10 is illustrated as of channel shape, but may take any other form, a variety of which are shown in the Car Builders' Cyclopedias, 1943, at page 995.

Instead of a bent rod forming a unitary tension member with two threaded nuts at its ends, there are two tension members of the general form shown in Fig. 3 made from the same sort of rod with integral upset heads at its respective ends. The heads are said to be integral upset to distinguish them from any form of head tending to weaken the tension members as the conventional tension member is weakened by the threading. The outer head 14 corresponds generally to the conventional hexagonal nut, and the inner head 15 is formed by two lugs extending generally at right angles to the length of the tension member and of a size to give the full strength of the tension member in service.

The brake heads 13, right and left, are conventional with one exception made necessary by the heads 15 on the inner ends of the tension members. Each brake head includes a sleeve portion 16 adapted to slip over and receive the corresponding end of compression member 10, and providing a seat 17 against which the end surface rests. Inclined to this sleeve portion and extending in part through it is another sleeve portion 18 for the tension member 11; and in order to permit the head 15 to pass through this sleeve portion 18, it is provided with lateral extensions or passages 19 which give the interior of the sleeve a form that will be called keyhole shaped. This sleeve 18 is at right angles to a wall 20, which forms the seat of the outer head 14 of each tension member and corresponds to the seat for the conventional hexagonal nut in the A. A. R. standard construction. Each head is also provided with a formation generally indicated by 21 to receive and make the brake shoes fast. Of course, some will prefer to make the actual brake head separate from the sleeve portions which serve to unite the adjacent ends of the compression and tension members, but this illustration is following conventional lines, and therefore the brake head is made in one with those sleeve portions.

The strut 12 is conventional in the seat 22 for receiving the intermediate portion of the compression member 10, the brake lever passage 23, and the openings 24 for the brake lever fulcrum at what will become the tension end. However, instead of a fork or transverse passage, as is conventional, the strut is provided with an enlarged casing 25 formed by top and bottom walls 26, inclined side walls 27, inclined end walls 28, and a base wall 29 forming a part of the strut proper.

The walls 27 are at right angles to the tension members 11 and are provided with keyhole slots 30 (Fig. 2) adapted to admit the inner headed ends 15 of the tension members 11. These keyhole slots have extensions 31 corresponding to

extensions 19 of the tubes in the brake heads. At right angles to these extensions 31 and on the inner sides of the walls 27 there are seats 32 formed as depressions between ridges or lugs 33, which cooperate with the lugs 15 to secure the tension members against rotation when the brake beam has been assembled.

In assembling this brake beam, the compression member, the strut, and the brake heads are brought together in the usual relationship, and this sub-assembly is put into the fixture or jig equipped with suitable means for bending the compression member to give it the desired camber required of the particular beam and, conveniently, a little more camber. The tension members are then put in final position and the bending pressure on the compression member is released. The tension members may be inserted to approximately the position shown in Fig. 5 as a preliminary to the bending operation which latter will serve to align the inner end of each of the tension members with the corresponding keyhole slot 30 in the tension end of the brake beam strut, or the bending operation can be performed first and afterwards the tension members inserted through the brake heads and into the sockets at the tension end of the strut. For want of a better term, the joint between the tension end of the strut and the tension members will be called a bayonet joint.

By giving the compression member a little excess bending, the inner ends of the tension members will be brought inwardly far enough to permit the heads 15 to be rotated to their final position opposite the seats 32 (Fig. 7) before releasing the bending stress, and when it is released the lugs 15 will seat in those recesses and automatically fasten the tension members against turning.

As an extra precaution and to meet the personal desires of some, an additional fastening means—such as a pin 33—may be inserted through one or both walls 26 of the casing 25 at the tension end of the strut and into or through the adjacent end of the tension member. As here shown, the pins 33 are shown passing through both walls 26, and the inner end of the tension member 11 in line with the lugs 15, but that is a matter of selection and really a matter of design for the engineer to suit the convenience of production without resulting in a weakness at the connection.

Any proper design of the construction here disclosed will eliminate all weaknesses such as are now formed in conventional brake beams by threading the ends of the tension members and peening over their extreme portions that project beyond the conventional hexagonal nuts.

When a brake head is to be replaced, it will only be necessary to put the compression member under a little bending stress when the pin 33, if present, can be removed and the tension member rotated 90 degrees and then withdrawn. After emplacing a new brake head, the operation will be reversed.

I claim:

1. In a brake beam, a compression member, a brake head on each end of the brake beam engaging an end of the compression member, each of said brake heads having a wall with an opening, a brake beam strut having one end secured to the center of the compression member and having at its other end two walls each provided with an opening facing one of the brake head wall openings, and a tension member extending

through each facing pair of openings to connect said strut with said brake heads, respectively, each end of each of said tension members having an integral enlargement thereon to prevent retraction of the tension member through the corresponding opening, at least one of the openings of each of said pairs of openings being non-circular and the adjacent enlargement on the corresponding tension member being non-circular and dimensioned to enter the non-circular opening at one rotary position of the tension member and to engage the wall around the opening at another rotary position of the tension member whereby with flexure of the compression member the tension member may be assembled by insertion through the non-circular opening and subsequent rotation.

2. A brake beam as claimed in claim 1, in which each of the walls having the non-circular opening is provided with a depression for seating the adjacent non-circular enlargement of the tension member and preventing rotation thereof.

3. A brake beam as claimed in claim 1, in which the non-circular openings are provided in the two walls of the strut.

4. A brake beam strut comprising a seat at one end for a compression member and having at its opposite end a pair of angularly related inclined walls defining a hollow chamber, each of said walls having a non-circular slot opening through

5

it and having on its interior surface a seat for holding the non-circular enlargement of a tension member after insertion through the slot and rotation.

5. A brake beam strut comprising a seat at one end for a compression member and having at its opposite end a pair of angularly related inclined walls defining a hollow chamber, each of said walls having a non-circular slot opening through it and having on its interior surface a seat for holding the non-circular enlargement of a tension member after insertion through the slot and rotation, said seat including a depressed portion for receiving said enlargement and thereby prevent rotation of the tension member.
